UNITED STATES PATENT OFFICE

FRANK R. McGEE, OF STEUBENVILLE, OHIO

FURNACE REGENERATOR

Application filed June 14, 1928. Serial No. 285,324.

This invention relates to regenerative chambers and checkerwork therefor and, while not limited thereto, relates to regenerative chambers for open hearth furnaces, and has for one of its objects the provision of a regenerative chamber of improved form whereby the gases will be distributed to and collected from the checkers in an improved manner.

Another object is to provide a novel form of checkerwork whereby a materially greater heat exchanging area is provided than in the standard form of checkers, and whereby all the checkers are evenly heated.

A further object is to provide an improved form of support for the checkerwork.

A still further object is to provide means for regulating the flow of gases through some of the vertical checker flues whereby the checkers will be evenly heated.

In the drawings:

Figure 1 is a sectional plan of a checker chamber constructed in accordance with this invention, taken on the line I—I of Figure 2.

Figure 2 is a sectional side elevation through the chamber.

Figure 3 is a transverse sectional elevation through the checker chamber.

Figure 4 is an enlarged sectional plan of a portion of the checkers of the checker chamber.

Figure 5 is an elevation taken on the line V—V of Figure 4.

Figure 6 is a sectional elevation taken on the line VI—VI of Figure 5.

Figure 7 is a large scale detail plan of several of the assembled checker bricks.

Figure 8 is an enlarged side elevation of one of the checker bricks.

Figure 9 is an enlarged plan of one of the checker bricks.

Figure 10 is an enlarged plan of several checker bricks, of a slightly modified form, in assembled position.

Figure 11 is a side elevation of several of the assembled bricks of Figure 10.

Referring more particularly to the drawings, the numeral 2 designates the regenerative chamber as a whole, which is of the usual outline, and has one end provided with a port

3 communicating with the downtake 4 of an open hearth furnace, while its other end is provided with a port 5 communicating with a conduit 6 leading to a stack and air supply conduit (not shown).

A plurality of transversely spaced checker supporting walls 7 extend longitudinally along the bottom wall of the chamber 2 and are provided with openings 8. The walls 7 are of constantly increasing height from the furnace end of the chamber toward the stack end thereof, so that their top faces are inclined upwardly in the direction of flow of the gases. The spaces between the walls 7 form a gas collecting and air distributing chamber 9 of constantly increasing area toward the outlet or stack end of the chamber, while the openings 8 form equalizing passageways for equalizing the pressure of the gases and air in the distributing and collecting chamber 9.

A checker supporting diaphragm 10 is supported on the walls 7 and is preferably formed from a plurality of horizontal layers of hollow tiles 11 laid up in high temperature cement. The tiles 11 may have roughened surfaces, if desired, so that the cement will form keys between the tiles, since the tiles 11 are adapted to be self-sustaining between the walls 7. The tiles of the several layers are laid up with their openings in vertical alignment so as to form vertical flues 12 which communicate with the vertical flues of the checkers to be described.

A checkerwork A is built on the diaphragm 10 and is composed of a plurality of intersecting vertically disposed rows 13 of cross shaped bricks 14. The bricks 14 may vary in detail but consist essentially of a pair of parallel arms 15 of relatively heavy, square cross-section and a pair of parallel arms 16 of relatively light or small and round cross-section and extending at right angles to the arms 15. The bricks 14 are laid up with their relatively heavy cross-section arms 15 extending vertically, and with their relatively light cross-section arms extending horizontally. The vertically disposed arms 15 of each layer of bricks of each row are arranged in alignment with and contact with the arms 15 of the adja-

cent layers of bricks in the same row, while the horizontal arms 16 of the bricks are spaced a short distance from the arms 16 of the next adjacent bricks. The arms 16 have their vertical edges beveled, as at 18, and the space between the ends of the arms 16 are so gaged that the beveled edges 18 of the arms 16 of the bricks of the intersecting rows will abut and be supported against each other. The space between the arms 16 of the bricks of intersecting rows form vertical flues 19, and the spaces between the intersecting rows of bricks form main vertical flues 20 which communicate with the flues 12 in the diaphragm 10.

By laying up the bricks 14 with the relatively heavy arms disposed vertically and in contact with the vertical arms of the abutting bricks of the same row, transverse spaces or openings are provided above and below the relatively light or reduced cross-section arms 16, which openings communicate with the vertical flues 19 between the ends of the arms 16 and with the next adjacent main flues 20, thus forming transverse passageways 22 which serve as equalizing and distributing passageways through which the gases may flow from one main flue 20 to the other, and through which the heated gases pass to the flues 19 between the ends of the arms 16.

The arms 15 of the bricks 14 are preferably interlocked with each other and, for this purpose, the lower arm 15 is provided with a recess 24 in its end wall, and the upper arms 15 have their end walls provided with a projection 25 so that the projection 25 of the upper arm of one brick is fitted into the recess 24 of the lower arm of the next brick above.

The checker supporting diaphragm 10 and the checkerwork A are of the same vertical height throughout, and the checkerwork terminates short of the top of the top wall of the regenerative chamber so as to provide a gas distributing chamber 26 of gradually reduced area, which causes a more even distribution of the gas than a chamber of equal size.

The lower ends of the flues 12 are provided with choke plugs 28, which serve to choke the flow of gases through the checkers and thereby build up a sufficient gas pressure to cause equal distribution throughout the checkers.

The novel form of the checkerwork A, resulting from the novel shapes of the bricks 14, provides for substantially forty-five per cent more heating surface than when checkerwork is formed from ordinary solid brick and, at the same time, provides a checkerwork in which materially less brick is used. The increased heating surface provided by the novel checker bricks 14 provides a more efficient regenerative chamber which absorbs more heat from the gases, and consequently gives off more heat to the air or gases to be heated than a standard regenerator.

In Figures 10 and 11 I have shown a slightly modified form of checker brick which has the edges of the vertical arms 15 rounded, as at 15^a, so as to increase the heating surface thereof, and the arms 15 of the bricks used to construct the transverse checker walls are notched, as at 16^a, to form seats for the unnotched ends of the arms 15 of the bricks used to construct the longitudinal checker walls. The rounded edges 15^a of the arms 15 serve to increase the size of the transverse passageways 22 between the checker flues 20, and the edges may be rounded in a more or less degree, as desired.

It will also be understood that the arms 15 of the bricks 14 may have their edges rounded, if desired, so as to increase their heating surface and also increase the size of the transverse passageways 22.

While I have shown and described one specific form of my invention, it will be understood that I do not wish to be limited thereto since various forms of checker brick may be used to form the novel form of checkerwork and various other modifications may be made without departing from the scope thereof, as defined in the appended claims.

I claim:—

1. In a regenerative chamber a plurality of vertically disposed transversely spaced and longitudinally extending checker supporting walls having transverse openings therethrough forming equalizing passageways for the gases, a horizontal checker supporting diaphragm supported on said checker walls and composed of hollow tiles laid up in high temperature cement, the openings in said tiles forming vertical flues through said diaphragm, a checkerwork supported on said diaphragm and having vertical and horizontal passageways therethrough and means in at least some of said vertical flues in said diaphragm adapted to regulate the flow of gases therethrough so as to build up a sufficient pressure resistance to the flow of the gases to compel an equal distribution thereof throughout the checkerwork.

2. In a regenerative chamber, a plurality of vertically disposed transversely spaced and longitudinally extending checker supporting walls having transverse openings therethrough forming equalizing passageways for the gases, said walls having their top faces inclined upwardly in the direction of flow of the gases, a checker supporting diaphragm mounted on said checker walls and composed of hollow tiles laid up in high temperature cement, the openings in said tiles forming vertical flues through said diaphragm, and a checkerwork supported on said diaphragm and having vertical and horizontal passageways therethrough, at least some of said vertical passageways registering with the vertical flues in said diaphragm, said diaphragm and said checkerwork being of

the same vertical dimension throughout their area so as to follow the inclination of the top of said checker supporting walls.

3. In a regenerative chamber, a plurality of vertically disposed transversely spaced and longitudinally extending checker supporting walls having transverse openings therethrough forming equalizing passageways for the gases, said walls having their top faces inclined upwardly in the direction of flow of the gases so as to form a gas collecting chamber of constantly increasing area toward the outlet of said chamber, a checker supporting diaphragm mounted on said checker walls and composed of hollow tiles laid up in high temperature cement, the openings in said tiles forming vertical flues through said diaphragm, and a checkerwork supported on said diaphragm and having vertical and horizontal passageways therethrough, at least some of said vertical passageways registering with the vertical flues in said diaphragm, and said diaphragm and said checkerwork being of the same vertical dimension throughout their area so as to follow the inclination of the top of said checker supporting walls and form a gas distributing chamber of gradually decreasing area.

4. A checkerwork for regenerative chambers and the like, composed of intersecting vertical rows of cross-shaped bricks, said rows of bricks being spaced apart slightly less than the width of one brick, said bricks having the ends of their horizontal arms spaced apart and having the ends of their vertical arms abutting the vertical arms of the next brick of the row in a vertical direction, and the horizontal arms of the bricks of the intersecting rows of bricks abutting for only a portion of their area so as to form open joints which cooperate with the shape of the bricks to form intersecting horizontal and vertical passageways at the points of intersection of the bricks of the intersecting rows of bricks.

5. A checkerwork for regenerative chambers and the like, composed of spaced intersecting vertical rows of solid cross-shaped bricks, said bricks being laid up so that the ends of their vertical arms abut the ends of the vertical arms of the next brick of the row in a vertical direction, and the horizontal arms of the bricks of the intersecting rows of bricks abut for only a portion of their area so as to form horizontal and vertical passageways at the points of intersection of the bricks of the intersecting rows of bricks.

6. A checkerwork for regenerative chambers and the like, composed of two series of vertical rows of solid bricks, said rows of bricks of one series of rows being arranged at right angles to the rows of the other series to form vertical flues, said rows of each of said series of rows being spaced apart not more than the width of a single brick, said

bricks having their end faces adjacent the side faces of the bricks of the row extending at right angles thereto provided with projections which abut said side faces, the portions of said end faces beyond said projections being spaced from said side faces to form transverse passageways between said vertical flues, and the adjacent ends of the bricks of each of the rows being spaced from each other so as to form other vertical flues, said last named vertical flues intersecting said transverse passageways.

In testimony whereof, I have hereunto set my hand.
